UNITED STATES PATENT OFFICE.

CARLO SCHLEIFER, OF NOVARA, ITALY.

MACHINE FOR COMBING TEXTILE FIBERS WITH INTERMITTENTLY-ROTATING NIP DRUMS.

Application filed January 9, 1928, Serial No. 245,454, and in Germany January 13, 1927.

Machines of the Schleifer type are known for the combing of textile fibers, (U. S. Pat. No. 1,408,780 and No. 1,425,059), upon which two or more intermittently rotating 5 drums are provided, which are equipped on their peripheries with a number of nippers. These nippers can close or open at a desired instant for the purpose of seizing in the required time the tufts or beards of the 10 fibers to be combed, and holding them fast or releasing them. The tufts of fibers delivered to the nippers on the successive drums are combed at the head and tail ends by revolving combing cylinders, and finally 15 delivered by the nippers of the last drum to a discharge device.

The present invention relates to improvements in combing machines of the type described above. These improvements consist 20 in subdividing the machine into as many independent units as there are nip drums, each of these units consisting of a machine frame in which one nip drum is arranged with its combing device and the auxiliary 25 members associated therewith, while special means are provided for varying at will the relative positions of the above mentioned units, both for the purpose of bringing them nearer together into a definite advantageous 30 working position so as to obtain in the combed product the sorting of the fibers according to their length, and for the purpose of moving them away from one another in order to facilitate inspection, repair or 35 cleaning.

One constructional form of the invention in its application to combing machines of the above-mentioned type with only two nip drums is illustrated diagrammatically and 40 merely by way of example in the accompanying drawings, in which:—

Figs. 1 and 2 show in side elevation, partly in section, two constructional forms of such improved machines according to the invention.

Figure 3 illustrates a detail.

For the purpose of facilitating the comprehension of the employments of the invention in combing machines of the above-mentioned type, the construction and the method 50 of working these machines will be briefly described and explained with reference to the constructional forms illustrated.

In the constructional example illustrated 55 in Fig. 1, the combing machine comprises

two drums 1 and 1', which are provided on their peripheries with nippers for the tufts of fibers to be combed. The nippers consist of a pair of movable jaws 2, 3 and 2', 3'. The drums 1 and 1' rotatably supported by means 60 of their shafts 4 and 4', are intended to rotate in the direction indicated by arrows, with an intermittent and synchronous movement, the angular amplitude of which is equal to the angle between two adjacent 65 nippers. With each cylinder there co-operate two combing cylinders 5, 6 and 5', 6', which revolve continuously and are so arranged as to correspond to the stopping position of two adjacent nippers. With 70 each of the said combing rollers there co-operate revolving brushes 7, 8 and 7', 8', which serve to remove the short fibers from the teeth or needles of the combing cylinders. With the said rotatable brushes there co-operate stripper rollers (doffers) 9, 10 and 75 9', 10', while an oscillatable comb 11 and 11' serves to remove from the last of these rollers the fleece of noil.

In the example illustrated in Fig. 2 there 80 is a simplified combing machine with a single combing cylinder 5 and 5' for each drum 1 and 1' and a single revolving brush 7 for both cylinders, as well as a single stripper or doffer 10' with its corresponding oscillating comb 11' for removing the fleece of noil.

The method of working of combing machines of this kind is substantially as follows:—

The ribbon 12 of fibers to be combed out is supplied at —a— to an open nipper 2, 3 of the drum 1. After the closing of this nipper and in consequence of a partial revolution of the cylinder, a tuft of fibers 13 95 is detached. The tuft is combed out at the head end on both sides or only on one side according as there are two combing cylinders 5, 6 or only one. At —b— the tuft, held fast by the still closed nipper of the cylinder 100 1, comes opposite to an open nipper 2', 3' of the cylinder 1', into which it is introduced by a rapidly oscillating bar or blade 14. This tuft is then seized by the nipper 2', 3', which closes while the corresponding nipper 105 of the cylinder 1 opens. In this manner the transfer of the tuft from one cylinder to the other is accomplished with reversal of the tuft. Next the tuft is combed at the tail end by the combing cylinders 5', 6', or 110

by the single cylinder if there is only one, whereupon it is seized at —c— and discharged by an appropriate discharging device.

5 Now according to the present invention each nip drum is arranged with its combing members and corresponding accessories inside an independent machine frame, while the various machine frames are so arranged 10 that the distance between them, and therefore also between the nip drums carried by them, can be altered.

Thus in the example illustrated in Fig. 1, the drum 1 and its combing cylinder 5 and 6, 15 and also the auxiliary devices 7, 8, 9, 10, and 11, are supported in a machine frame 15, which is distinct from the frame 15' which serves to support the drum 1' and the similar devices belonging to it. Moreover this latter machine frame 15' is slidably arranged on guides or slides 15^a, which project in a longitudinal direction from the first frame, consequently the frame 15' can be moved 20 parallel to itself in such a manner as to vary 25 the distance between the two frames and therefore between the drums 1 and 1'. The smallest distance between the two frames 15 and 15' can be regulated at will by means of screw stops 16, which are adjustably secured 30 to one of the two members, for instance to the member 15', and bear against the corresponding member 15 at the end of the movement of approach. In the example according 35 to Fig. 2 the arrangement is similar in the main, except that those auxiliary devices such as the brush 7 which are common to the two drums 1 and 1' may be provided optionally on one frame or the other.

In consequence of the arrangement hereinbefore described, the two units of which the machine consists can be adjusted in any desired manner, the frame 15' being displaced on the guides 15^a of the frame 15, as illustrated in dotted lines in Fig. 1. This shifting apart, which can be effected to an optional extent, only limited by the length of the guides, presents advantages for the inspection, the repair or the cleaning of the two units. By the aid of the stops 16, whenever the two units are moved nearer together they are readjusted afresh into the exact position required for working. The object of the adjustable stops 16 further consists in enabling the minimum distance between the two cylinders 1 and 1' during the working to be altered in almost imperceptible stages, this being for the purpose of altering the combing effect which is intended to be obtained. This will be clearly seen by considering Fig. 3, in which one nipper 2, 3 of the drum 1, and, in dotted lines, different positions of the corresponding nipper 2', 3' of the drum 1', are shown in the correspondence with zone —b—, in which the delivery 60 of the tuft 13 from one cylinder to the other

takes place with reversal, this tuft being diagrammatically illustrated as consisting of fibers of different lengths. It is clear that the nearer the nipper 2', 3' is brought to the nipper 2, 3, the greater will be the quality 70 of fibers seized and retained during the ensuing combing of the tail end of the tuft, while by increasing the distance between the said nippers, the fibers that are below a particular length are not seized, and will pass 75 into the noil during the subsequent combing. By regulating the distance between the nip cylinders it is thus possible to eliminate 80 from the combed material the fibers that do not attain a certain length.

Although the invention is only shown in its application to a combing machine with two nip drums, it will be immediately recognized that it is also applicable to combing machines of the same type with any number 85 of cylinders. It is moreover also obvious that the invention is by no means limited to the diagrammatic arrangements described and illustrated but that it may undergo, without departing from its fundamental 90 idea, all the modifications which are required in practical use.

I claim:

1. A machine for combing textile fibers, comprising a plurality of units, each unit 95 consisting of a frame member, a nip drum and associated elements, and means to permit the adjustment of the frame members to and from one another to increase and decrease the distance between the drums to 100 control the length of fiber going to the noil.

2. A machine for combing textile fibers, comprising a plurality of cooperating units, each unit comprising a frame member, a stepped nipper drum mounted in the frame, and rotary combing units, rails on which at 105 least one frame, on which a drum and associated combing mechanism is mounted, is movable to and from the other frame, and adjustable stops, said frames being freely 110 movable apart, but limited by the stops to their position of approach toward one another.

3. A machine for combing textile fibers, comprising a stationary frame and a movable frame, a stepped nipping drum and associated rotary combing members mounted on the stationary frame, a stepped nipping drum and associated rotary combing members mounted on the movable frame, the 115 nippers of one drum receiving combed tufts of fiber from the other drum, said movable frame being free for movement away from the stationary frame, and an adjustable stop on the movable frame to control the space 120 between the frames when in operative relation one to the other.

In testimony that I claim the foregoing as my invention, I have signed my name.

CARLO SCHLEIFER.
